UNITED STATES PATENT OFFICE.

MATTI PIETILÄINEN, OF HELSINGFORS, FINLAND, RUSSIA.

HAMMOCK.

1,071,954.

Specification of Letters Patent.

Patented Sept. 2, 1913.

Application filed May 1, 1912. Serial No. 694,445.

To all whom it may concern:

Be it known that I, MATTI PIETILÄINEN, manufacturer, subject of the Grand Duchy of Finland, residing at No. 6, Holmniäs-gatan, in the city of Helsingfors, Finland, Russia, have invented certain new and useful Improvements in Hammocks, of which the following is a specification.

This invention relates to hammocks, and 10 has for its object to provide a hammock which can be easily attached and regulated as to its length and depth without the necessity of unfastening the hammock.

The hammocks at present in use are provided at one end or both ends with cross-pieces intended to keep the hammock extended, and in order to also keep the middle portion of the hammock extended, separate marginal cords are provided which run 20 along the outer edges of the hammock from end to end, and separate ropes are used for attaching the hammock. The special object of the rings is to hold the main parts of the hammock together. The principal 25 drawback of such a hammock lies in the fact that the outer meshes of the net which pass through the holes in the cross-pieces are specially subject to rapid wear, as they are always rubbing at the same places 30 against the sharp edges of the said holes. Moreover, the hammock itself is more extensible than the said marginal cords, so that it becomes impossible to adjust the length of the hammock, as the marginal 35 cords are connected to the rings. Consequently, when the hammock is in use, the entire weight of the person in the hammock rests on a few cords in the middle of the hammock, whereby said cords are still more 40 stretched besides having to support a great load.

The hammock, made in accordance with my invention, can be readily adjusted to the desired length, and also the depth of the 45 hammock can be regulated at will without that the hammock need be unfastened. This object is attained by so assembling the main parts of the hammock that those parts which are most subject to wear do not

always occupy the same position relative to 50 each other, so that the entire hammock will be subjected to more or less uniform wear.

In the drawing Figure 1 is a side view of one form of my new hammock with the cross-pieces set far apart, Fig. 2 is a similar 55 view showing the cross-pieces nearer together. Fig. 3 is a plan view of one end of the hammock, Fig. 4 a section through one of the tension pieces.

The hammock consists of the net *g*, in 60 place of which, if desired, a cloth can be used, the cross-pieces *f* and the tension pieces *h*, the cross-pieces being intended to keep the hammock extended and to so support the same that the tension is distributed 65 over the entire cross-piece. The cross-pieces by means of the apertures *r* allow for the adjustment of the length and depth of the hammock.

The tension pieces *h* are intended to connect the suspension and the tension ropes in 70 such a manner that these ropes may be joined to form a single rope, *a*, *b*, *c*, *d*, *e*, which, as shown in the drawing, takes the following course: First it is drawn through 75 the openings *i* in one of the tension pieces *h*, then through some of the holes *r* in the corresponding cross-piece *f*, then through the hole *l* in the projection of the tension-piece *h*, and then through the outside holes *r* of 80 the said cross-piece to the other cross-piece, etc., thus extending around the entire hammock, forming the marginal cords and the tension cords *b*, *c*, and *d*, and the suspension 85 cord *a*. By means of this arrangement one 90 can adjust the cross-pieces *f* and the tension-pieces *h* to regulate both the length and depth of the hammock by increasing or decreasing the distance between the two cross-pieces on one side, and between the places of attachment and the tension-pieces on the other side. By the arrangement as described, the suspension-cord can also be increased or decreased either over its entire length or at 95 one side of the hammock only.

I claim as my invention:

A hammock comprising in combination with a net and two cross-pieces adapted to

hold the ends of the net extended and provided with apertures, two tension-pieces, one located at each end and provided with holes, and a single rope passed successively through the holes in said tension-pieces and the apertures in said cross-pieces, so as to extend around the entire hammock forming two marginal cords, tension cords and suspension cords, permitting the relative adjust-

ment of the said cross-pieces and tension-¹⁰ pieces.

In testimony whereof I affix my signature in presence of two witnesses.

MATTI PIETILÄINEN.
